DIVER'S HELMET

Richard F. Jones, Santa Barbara, Calif., assignor to
Agonie Engineering, Santa Barbara, Calif.

Filed June 15, 1970, Ser. No. 23,496

Term of patent 14 years

Int. Cl. D2—03

U.S. Cl. D2—231

FIG. 1

FIG. 2

FIG. 3

FIG. 1 is a side elevational view of a diver's helmet showing my new design, the side opposite being reversely similar;

FIG. 2 is a top plan view; and

FIG. 3 is a rear elevational view.

The side opposite that shown in FIG. 1 is a mirror image of FIG. 1.

I claim:

The ornamental design for a diver's helmet, as shown and described.
